DOOR LOCK

Charles A. Dies, Chicago, Ill.

Application February 10, 1937, Serial No. 125,142

3 Claims. (Cl. 70—129)

My invention is an improvement in door locks, and relates to the general class of latches in contradistinction to the use of sliding bolts in connection with ordinary door locks.

It is customary to provide the doors of apartments and other dwelling houses, as well as stores, with locking means in addition to the ordinary mortised lock having a spring-actuated latch and sliding bolt, for further security, and it is therefore the main purpose of my invention to provide locking means that can be readily applied to a door and easily removed so that a temporary occupant of an apartment or dwelling may easily remove the lock and use it on the door of another apartment or dwelling occupied by him, although it may be also used as a permanent attachment to a door.

A further object of my invention is to provide a removable door lock of comparatively simple construction that will not only dispense with the use of springs, that are liable to get out of order, but will also include peculiar means for raising and lowering the latch plate movable into locking position by gravity.

With these principal objects in view my invention contemplates the provision of a vertically sliding latch plate enclosed within a casing secured to the inner side of the door and having projecting hook shaped members adapted to engage loops in a keeper plate, in association with a turnbutton for manipulating the latch plate from the inner side of the door, and a removable key for operating the turnbutton from the outer side of the door, as hereinafter fully described and specifically set forth in the appended claims.

In the accompanying drawing:

Figure 1 is a front elevation of a door lock constructed in accordance with my invention.

Fig. 2 is a vertical sectional view on the line 2—2 of Fig. 1.

Fig. 3 is a detail sectional view of the lock on the line 3—3 of Fig. 2.

Fig. 4 is a detail perspective view of the sliding latch plate.

Fig. 5 is a detail sectional view of the turnbutton forming a part of the lock.

Fig. 6 is an end view of the turnbutton.

Fig. 7 is an end view of a turnbutton illustrating a modification of the key hole, and

Figs. 8 and 9 are detail views of different forms of keys usable in connection with the lock.

In carrying out my invention I employ a two-part casing comprising a flat plate 10, to bear against the door 11, and a housing plate 12 hav-

ing opposite flanges 13 by which it is attached to the aforementioned plate by studs 14, with screw holes 15 through the plates for attachment of the lock casing to the door as by means of screws 16, and within this casing there is slidably mounted a latch plate 17 having hook-shaped members 18, 18 projecting from one end of the lock casing to engage a keeper plate 19 having spaced apart loops 20, 20 with which the hooks of the latch engage. For guiding the latch plate in the lock casing there is a vertical rib 21 formed on the plate 10 received in a vertical groove 22 in said latch plate, and in order that this latch plate may be reversed for application to a door opening either to the left or right it is provided with grooves, 22, at opposite sides thereof. The latch plate has free movement in the casing so that it will drop by gravity into engagement with the loops of the keeper plate, and therefore it is desirable to have a thick plate for the required weight in operation.

To raise and lower the latch plate it is provided with an opening 23 to receive the shank 24 and lug 25 of a turnbutton 26, the shank extending through the cover plate 12 and being of such length as to locate the knob away from the lock casing for manipulation, with a sleeve 27 interposed between the knob and lock casing. By reference to the drawing it will be noted that the opening in the latch plate is of a particular shape for the operation of the lug on the turnbutton; that is to say, the opening is of a width vertically to correspond with the length of the lug and cross-section of the shank, and has converging curved walls or lug engaging surfaces 28, 28 extending outwardly from a straight wall 29 at the opposite side of the lug from said curved walls, with the latch plate confined to a direct vertical movement by the rib or spline hereinbefore referred to. It is preferable to have straight horizontal walls immediately above and below the shank and lug between the curved walls and vertical wall referred to, so that when the lug is turned upward to raise the latch, or downward to lower the latch, the turning of this turnbutton by accidental movement of the latch plate, especially in the raised position of the latter, will be prevented, and the lower straight horizontal wall will prevent lifting of the latch plate to unlock the door independently of a manual operation of the turnbutton, as for instance by an instrument passed through the crack between the door and jamb. As will be obvious, the straight wall 29 limits the throw of the lug

to one direction or towards the curved walls with which its outer end engages in the normal operation of the latch plate.

The turnbutton provides for operating the slideable latch plate from the inner side of the door, and it will be noted by reference to Fig. 3 that when the latch plate is raised as shown in dotted lines, in unlocked position with respect to the keeper plate, it rests directly on the outer end 10 of the lug so as to be firmly supported thereby, and to lock the door the turnbutton is given a half turn clockwise so as to release the latch plate and permit it to drop by gravitation, the lug then being in the position shown in full lines 15 to prevent raising said latch plate in any other manner than by means of the turnbutton.

To operate the turnbutton or lug from the outer side of the door it is only necessary to provide the inner end of the shank with means for 20 the engagement of a key that will act to manipulate said turnbutton, as for instance a keyhole, such as illustrated in Figs. 6 and 7, may be formed directly in the end of the shank, and either a straight key, 30 (Fig. 9), or a key having 25 a flexible shaft 31 (Fig. 8), used in connection therewith. When a key with a flexible intermediate portion or shaft is used the opening through the door for the insertion of the key to engage the turnbutton is serpentine, as shown 30 in Fig. 2, thus requiring a key of this kind to be used in the operation of the lock. To provide a serpentine passageway for the flexible key I employ a bent tube 32, and for convenience in applying this tube to the door it is welded in a 35 cylindrical bushing 33 inserted in a corresponding opening through the door and held in place from being withdrawn from the outer side of said door by a circumferential flange 34 at its inner end. By this arrangement it is only necessary to drill a straight hole through the door 40 to receive the bushing and countersink the inner end of the hole to receive the flange so that the lock casing will retain the bushing in place, the usual escutcheon 35 being secured at the outer 45 side of the door to cover the outer end of the bushing.

Instead of operating the turnbutton by the simple means of a keyhole in the end of the shank of said turnbutton I prefer to provide the shank with a turnable member requiring several 50 turns of the key before positive operative engagement of the parts. This arrangement is illustrated in Fig. 5 of the drawing in which the shank 36 of the turnbutton is recessed at its inner end to receive an internally threaded collar 37 fixed therein to terminate a short distance from the inner end of the recess, and in connection with this collar there is a turnable plug 38 having a keyhole 39 at its outer end and a 55 peripheral flange 40 at its inner end, the latter playing in the space between the collar and inner end of the recess so that several turns of the plug will be required before it will abut against the opposite stops for responsive movement of 60 the turnbutton. The engaging threads are pitched so that in lifting the latch to unlock the door the key is turned clockwise until the turning of the plug is stopped by abutting the inner end of the recess (see Fig. 5) when a further 65 half turn of the key and plug will cause the lug to engage the upper wall of the opening in the latch plate and lift the latter to the position shown in dotted lines in Fig. 3. Likewise, to lower the latch plate will require the key to be 70 turned several times counterclockwise or until 75

the flange on the plug engages the inner end of the collar when a further half turn will lower the latch plate into locked engagement with the keeper plate.

From the foregoing description, in connection with the accompanying drawing, it will be seen that I provide a very simple form of door lock in which the hooks of a vertically movable latch plate engage loops of a keeper plate on the door jamb to securely fasten or lock the door closed, and that to unlock the door from the inner side the turnbutton is manipulated to lift the latch plate, while from the outer side of the door it will require a key to operate the turnbutton, the locking of the door from the inner or outer side thereof being accomplished in like manner to lower the latch plate. In either position of the latch plate it is firmly held by the lug projecting in a vertical plane from the shank of the turnbutton. Although the weight of the latch plate will cause it to be lowered by gravity it will be noted that this operation is also effected by the lug of the turnbutton engaging the lower curved wall of the opening in said latch plate, and in locking the door the turnbutton should be operated for the positioning of the lug vertically to prevent lifting of the latch plate by way of the projecting hooks. In other words, when a door is locked by means of my improved slideable latch plate and turnbutton it can be unlocked only by the operation of the turnbutton, and by providing the serpentine passageway for the key there is additional security against any one breaking into the building, for this will not only require the use of a flexible key but the winding passageway obscures sight of the keyhole. Furthermore, any attempt to open the door by one unfamiliar with the operation of the lock would be met by the peculiar key engaging means associated with the turnbutton requiring several turns of the key, thus serving to confuse the person making the attempt.

The lock may be used as a fastening means in addition to the ordinary mortised lock, or as the only means for locking a door, swinging window, or other movable part of a building or other structure.

I claim:—

1. A door lock comprising a casing, a vertical spline on one of the plates thereof, a latch plate slideable vertically in the casing and having vertical grooves in opposite sides thereof cooperating with the spline for adapting said latch plate to be reversed in the casing to accommodate doors opening to the right or left, hook-shaped members projecting from the latch plate beyond the casing for engagement with a keeper plate, an opening in the center of the latch plate, and a turnable element having a lug working in the opening to engage the upper and lower edges of said opening for raising and lowering the latch plate coacting to hold the latter in the respective positions thereof.

2. A door lock comprising a casing, a latch plate slideable vertically in the casing and having members projecting therefrom to engage a keeper plate, an opening through the latch plate presenting spaced apart upper and lower walls, a turnbutton having a shank extending into the lock casing, a lug projecting from the shank and working in the opening between the aforesaid upper and lower walls of the latch plate to raise and lower the same, a recess in the inner end of the lug, a threaded plug turnable in the recess for independent longitudinal movement therein,

and means associated with the turnbutton and plug for limiting the movement of said plug to require several turns thereof from one operative position to the other for responsive movement of the lug.

3. A door lock comprising a casing, a latch plate slidable vertically in the casing and having members projecting therefrom to engage a keeper plate, an opening through the latch plate presenting spaced apart upper and lower walls,

and a turnbutton having a lug working in the opening between the aforesaid upper and lower walls to raise and lower the latch plate, the inner end of the lug having a recess therein, an internally threaded collar fixed in the recess, an apertured plug in threaded engagement with the collar, and means for limiting the movement of said plug to require several turns for responsive movement of the lug.

CHARLES A. DINE. 10
